UNITED STATES PATENT OFFICE.

HERBERT J. ADAMS, OF BATTLE CREEK, MICHIGAN.

CIRCLE-GAUGING INSTRUMENT.

Application filed June 7, 1920, Serial No. 387,241. Renewed May 28, 1923.

To all whom it may concern:

Be it known that I, HERBERT J. ADAMS, a citizen of the United States, residing at Battle Creek, in the county of Calhoun and 5 State of Michigan, have invented a new and useful Improvement in Circle-Gauging Instruments, of which the following is a specification.

The purpose of my invention is to provide a compact and efficiently operative instrument in which are combined means by which:

All circles and arcs thereof that mechanical and civil engineering draftsmen may 15 need to gauge, measure or draw, of range in size between a straight line and a circle of a half inch or less in diameter;

For measuring, or by its aid determining the lengths of arcs and their radii, and their 20 value in degrees;

For setting off the degrees of the central angles of circles and ruling angles equivalent thereto of segments of circles;

For reproducing curved lines already 25 drawn at the same or different scales;

Providing in a single instrument the means for accomplishing drafting that now requires the use of a large number of pieces of drafting equipment such as fixed curve 30 rules, circle ruling devices of limited range of applicability, and protractors.

I attain these objects by the mechanism and associated objects illustrated in the accompanying drawings, in which:

Figure 1 is a plan view of my invention as it appears flat on the drafting board, and shows in dash line changed positions of the principal moving members. Fig. 2 is a sectional view of the instrument through line 40 X—X, Fig. 1. Figs. 3 and 4 are respectively plan view and section of the transverse plate and channel along which it slides, latch plate and arrangement of the center pin. Fig. 5 is an elevation of the laterally 45 tapering sleeve which controls the height of the center pin. Figs. 6 and 7 are respectively plan and sectional details showing the bearing ball frame supporting feet 42, and the support for guide bars 5. Figs. 8 and 9 are respectively end and sectional views of the slow-moving screw ribbed turning knob. Figs. 10, 11 and 12 are vertical and sectional details of the connection of the stay bar 13 with the flexible bar 6. Figs. 50 55 13 and 14 are perspective views showing the

means on radial arms 7 for their sliding engagement with bars 5. Numbered parts herein are so numbered in the views.

The angle bar 1, slashed and bent into suitable shape, with the lips of the slashes 60 securely riveted or bolted together, the plate 2 fastened thereto by bolts 3, and having one edge concaved in right and left intersecting divisions which serve as guides 4, 65 hereinafter referred to, the pair of curved guide bars 5 supported by the bars 45 and the ends of the angle bar, and also herein-after referred to, and a channel 17 fastened to bar 1 and plate 2 in line directed midway between the right and left guides, 70 constitute the framework of my invention, its operating position being flatwise on and about the drafting board. I find it convenient to form the angle bar to describe three angles of 120 degrees each, and the edge 75 of plate 2 opposite the guides thereon may describe a straight line directed towards corresponding points on the outline of the frame, so that angles of 30, 60, 90 and 120 degrees can be conveniently set off by the 80 frame alone.

Except where obviously unsuitable, or otherwise indicated, all the parts of the instrument are preferably stamped from sheet metal.

I provide the normally straight flexible bar 6, which has fastened to its ends the arms 7 which are provided at one end with the perforated guide lugs 8 (Fig. 14) adjacent to the bar, the latter being fastened 90 to the arms by the inverted channels, or bights 12, which grip it. Said lugs 8, and lugs 9 formed at the opposite ends of the arms are provided for sliding engagement of the arms with the bars 5 and guides 4 respectively, lugs 8, in preferred construction (Fig. 14), overlapping bars 5, and being flared for required play for the swing of the arms in their travel along guides 4, 95 while the downwardly projecting hooks 100 provided on pull rods 27, hereinafter mentioned, serve to hold the arms in close sliding engagement with bars 5 throughout their length. The lugs 9 terminate in pointers 10 (Figs. 1 and 13) hereinafter 105 referred to. The inner edges 11 of said arms are in line perpendicular, or normal, to the ends of the curvable portion of bar 6. That bar is preferably made of spring steel of the greatest uniformity of texture 110

known to commerce, and it stands edgewise to the drafting board and the planes of said arms. Movement of the arms forces bar 6 into uniform curves.

5 The stay bar 13 is provided, having guides thereon for sliding engagement with the circular guide 14 which is fastened to the frame clear of the swinging movement of arms 7 and centers at the midway point of 10 bar 6, the stay bar extending to that point and carrying pivoted to it vertically the clip 15 which impinges on the top of the former bar; so that downward pressure on the bar 13 effects steadyng of the bar 6, 15 to clear either side of which, in straight or curved form the stay bar 13 may be swung.

The points of contact of arms 7 with guides 4 are in line with said inner edges 11, said contact being maintained by the 20 tension of bar 6, since said guides serve to swing the arms to force the bar into curve formations. The ends of bar 6, by means connected therewith hereinafter described, are simultaneously started and swung in 25 unison along said guides to the extreme curved position of the bar, wherein lugs 9 meet at the intersecting point of guides 4, or are stopped at any intermediate position (dash line Fig. 1), said arms 7 being 30 each swung 90 degrees in total movement; and at such meeting position said inner edges are in line with each other and said intersecting point, and on the line of the chord of said extreme, or half circle, formation, said bights 12 having been in line 35 of the tangents, and said inner edges in line of the radii in all of the curve formations of bar 6 in such 90 degree swing, said guides 4 and 5 being geometrically de- 40 signed and located to dispose the arms in positions with respect to said bar which enforce therein uniformity of curve formations throughout, guides 4 enforcing arc relation of curve to tangent, while guides 45 5 enforce arc relation of curve, chord and tangent. So that in any of said curve formations any portion of the curved bar will register exactly on a line drawn along any other portion thereof. A simple test of 50 the effects of certain kinds of control on a bar similar to bar 6 may be found in employing a flexible bar of uniform texture and dimensions, say a flexible machinist's rule. By simply pushing its ends towards 55 each other without gripping them it will be noticed that the end portions will remain straight or only slightly curved, while towards the center of the bar it becomes bowed to a short curve formation. 60 On the other hand, by gripping the ends, and while pulling them away from each other forcing the ends into curves, the central portion of the bar will form a comparatively flat, but irregular, curve. Such 65 formations are produced by casual or arbit-

rary control as distinguished from the geometrical control gauged by the properties of circles necessary for producing in the bar uniform curves. The bar 6 will overcome considerable friction and return 70 to a straight line formation upon being released from bowed position. Guides 4 are in form and position in my invention describing a line which would be intersected by equal length sectors of radii of a succession of arcs of gradually shortened circles of length equal to one half the length of the bar imaginable between a straight line and a curve of the greatest degree possible to either half, which is a one fourth 75 circle in my construction. The guides 5 have the effect of describing a line which would be intersected by the ends of the above mentioned succession of arcs extending as in the above case from the midway point of the bar which is always stationary. But for convenience in the use of the instrument guides 5 are set away from the ends of the flexible portion of the bar 6 at 80 the point of the flattest curve formations a short distance on the tangent thereof, as shown in Figure 1, and swings gradually nearer to lines at right angles to the successive chords, and according as the tangential angles increase in degree. Hence 85 the necessity for the flare in lug 8 mentioned which allows for the necessarily increasing obliqueness of the positions of the tangent lines across bars 5.

A scale, 16, of 90 degrees, shown in part in Fig. 1, is arranged along one of the guides 4, preferably the left hand one as shown and for reasons hereinafter indicated, for indicating by the corresponding pointer 10 on arm 7 the number of degrees bar 6 has been curved from position at rest, the number per degree of curve equalling the number describing half the length of the bar, the outside end of the scale being 90 zero, while the spaces thereon become gradually narrower towards the inner end in agreement with the shortening of the curve formations enforced by the arms 7 in their progress along guides 4. The number of degrees to be pointed off on the scale for each degree of curve depends upon the length of said bar, such number of degrees being increased or decreased by multiplication or division to indicate respectively the 100 number of degrees at which the bar should be set to accommodate it to the desired curve of a smaller or larger scale of measurement than that adopted for the instrument, preferably in my construction that obtaining in the United States for curve formulae, i. e. 100 feet to the inch.

A scale 40 (shown in part, Fig. 10) is arranged along bar 6 for measuring the length of any arc or portion thereof formed by it, and for verifying and proving the 110 115 120 125 130

- curves gauged thereby, such scale being also convenient in connection with radius arms 7 for use as a protractor by pointing off on bar 6 the required number of degrees to 5 the unit on the scale for the degree of curve to which the bar is set up, said radius arms being used, upon registering the bar on the curved line, for drawing sectors of the legs of the desired angle. 70
- 10 The bar 6 may be of any length for convenient use on a drafting table; yet the convenience of the scale 470 depends upon the length of the bar. If the bar is 9 or 18 inches long, for a degree to a space of 15 the scale, when it is set up to half a circle, they should be graduated respectively to 20ths and 10ths inches, such arrangement being convenient for civil engineers, the longer being especially adapted for railroad 20 work. If it is desired for mechanical drafting to have the scale spaced to 16ths of an inch, a bar $11\frac{1}{4}$ inches long would have spaces equal to 180 degrees at the half circle formation, and be convenient for both 25 the above classes of work. Bars of other lengths could have a scale for lineal measurement on one side of the bar and a scale for degrees on the other. According to the formula mentioned a bar of any length 30 when set to a 1 degree curve would describe an arc having a central angle of as many degrees as there were inches in its length. A bar 15 inches long with a scale thereon spaced to 12ths of an inch, equalling 180 35 spaces when at the half circle, would be especially convenient as a protractor, since from the one degree curve formation it would be possible to set off an angle of $\frac{1}{12}$ th of a degree, or 5 minutes. 40 The end walls of channel 17 continue upward forming lugs 18 which have corresponding slots extending below the top of the channel. A screw, 28, carrying turning knob 29, extends lengthwise through the 45 channel and is provided with annular grooves near its ends affording the screw revolving seating in said slots and confining it longitudinally in the channel, while means hereinafter mentioned confine it vertically therein. 50 Plate 22 rests on and extends to the right and left of said channel correspondingly, being adapted for sliding movement along the same, and carries rigid beneath it auxiliary channel, or sleeve, 23 (Fig. 4) 55 which slides in channel 17 and encloses the screw, and serves to hold the plate on and guide it along the channel, the end portions of said plate being turned down and provided with openings 24 in which the 60 hook-shaped lever arms 25 slide, said lever arms being pivoted to the wings 26 of the channel, while their opposite ends have pivoted to them pull rods 27 provided with hooks, or offsets, hereinbefore mentioned, 65 which pass through the holes in lugs 8; so that movement of plate 22 along the channel swings the lever arms and changes the formation of bar 6. A portion of the lever arms which have contact with the plate is curved, subjecting the lever arms to centrifugal reaction as the openings progress along them, which advances their ultimate, or functional, ends over longer arcs than the arcs of the same radii between whose subtending radii the fulcrum moves. 75
- Plate 22 is surmounted over the channel by lug 30 (Fig. 4), pivoted to which is latch plate 31 which in turn carries pull lug 46, and has at one end a forked tongue projecting downward at the edge of plate 22 into the channel adapted for engaging the threads of the screw, said latch plate being adapted to tip into and out of such engagement, and being provided with release lug 32 between which and plate 22 tension spring 33 is anchored for automatically latching the latter plate on the channel subject to releasing pressure on either lug 32, or 46 in connection with opposite pressure respectively against the forward or rearward end of the channel. Plates, or caps, 20 and 21 which serve as pull lugs in moving plate 22, as above, are fitted to said lugs 18 and extend into the annular grooves on the screw for completing close bearings 90 therefor in the channel, the pressure required being conveniently applied by thumb and finger of the operator, said caps correctly extending sufficiently high above the channel to afford such purchase. Screw 28 100 serves as a slow-moving screw affecting directly the latch plate by turning knob 29 for setting the pointer 10 up to the exact point desired on the degree scale 16, or stopping the arms 7 at desired positions by 105 reference to members thereon hereinafter mentioned.
- The turning knob has ribs parallel with the screw and equally spaced apart so that the knob can be turned rib by rib by a finger or thumb alone, and its revolutions tallied by divisions thereof, enabling the operator, by reference to the known number of revolutions required for a space on said degree scale, or scale 44 hereinafter described—a matter usually of easy mental calculation—to move said pointer or other members to desired positions between graduation marks on the adjacent measuring scales. 110
- Plate 34 (Fig. 4) is provided which has a bight 20, serving as pull lug and screw bearing as hereinbefore mentioned, and passes around the point dividing guides 4 and is fastened to plate 2 beneath it by the 115 same means of fastening as is employed for the channel 17. Extending through a sleeve, 19, swaged in holes in vertical line in plate 34 is center pin 35 which is, with said sleeve 120 let into said dividing point a distance equal 130

to $\frac{1}{2}$ its diameter. The pin is adapted to revolve in the sleeve, and has a needle point at its lower end and a head at the top. Enclosing the pin between its head and plate 34 is the laterally tapering sleeve, or wedge, 36 which is movable transversely on the pin for raising and lowering the same from and to the drafting board, in which lowered position said needle point may be thrust into the board for revolving the frame thereon.

Since a half circle formation is the shortest curve possible in my invention with the flexible bar 6 of convenient length for general use, I complement such capacity by the use of nearly all of the parts involved therein by providing bar 37 (Fig. 1) supported along and a little above one of the arms 7, preferably the right hand one (assuming bar 6 to be at the forward side of the instrument) by fastening a lug provided thereon at its center to a corresponding upwardly projecting lug on the arm 7. The bar extends nearly to bight 12 and to lug 9, leaving said arm edge 11 clear for ruling along it. Said bar 37 has offsets at each end projecting over the drafting board in which are provided clear of said arm the openings 38 adapted for seating marking implements therein by providing bar 37 Fig. 1 (sup- 30 vent flow of ink from such instrument there- to. Adjacent to said openings are provided the upwardly projecting and flaring walls forming sockets 39 for steadyng such implements upright. Said bar 37 is vertically 35 flexible from the center outward, permitting depression of said seats to such greater or less extent as is necessary for the implement to reach the drafting paper according to the width of line the implement is fixed to produce, affording equally firm and definite seating in case of differing widths of line. The seats are used in connection with said center pin when sticking the drafting board and forming an axis around which the frame 40 may be revolved, for guiding such implements about the pin in gauging and ruling circles or segments thereof.

I avoid in large measure the soiling drag that would be otherwise occasioned by the instrument thus far described in its contact therewith in moving it about, and avoid in large measure the friction otherwise to be encountered in revolving it about the pin, by providing units of the following device 50 at appropriate points (Figs. 1, 6 and 7); a diaphragm, 41, having a round hole in its floor and being provided with a shank which is fastened to the under side of the frame, preferably underneath plate 2, in which is 55 a corresponding hole. Enclosed in the dia- phragm is bearing ball 42, in diameter greater than the depth of the diaphragm. Ten- sion plate 43 is fastened on top of the frame by bolt 3, and at rest bears against the upper 60 hole and, subject to overcoming downward

pressure on the frame, holds the ball to protrusion through the lower hole, but not far enough to deprive it of revolving play therein, though extending below the lower plane of the instrument, adapting the ball 70 to hold adjacent portions of the instrument clear of the drafting board. Upon the frame being depressed to the board by overcoming the tension plate the ball is forced to pro- trude through the upper hole. Though the frame may be revolved directly by hand, with the ball supports it is easily revolved, especially in case of the larger circles traced or ruled by the pen seats, by lateral pres- 75 sure of the seated marking instrument against the seats.

A scale, 44, (Fig. 6) is arranged along guides 4 and 5 adjacent to the pen seats by which may be indicated respectively, in con- nection with pointer 10 and the outer pen 80 seat, the distances of the inner and outer pen seats from the center pin at any distance the arms 7 may be stopped along said guides, thus indicating the radius of the arcs or cir- 85 cles gauged or formed by the use of the pen seats, the scale having no reference to the actual distance travelled by the pointer along guide 4, but only to the actual radial 90 distances of the pen seats from the center 95 pin.

In each of the several models which I have and have experimented with in perfecting my invention I estimate that the bar 6 em- 100 ployed in each has been sprung to a half circle formation several hundreds of times without discovering harmful deformation thereof, due largely no doubt to maintaining the uniformity claimed for the curve forma- 105 tions.

Having thus described my invention, what I claim as new, and desire to secure by Letters Patent, is:—

1. In a circle gauging instrument, includ- 110 ing a frame work adapted for being moved about or revolved on a drafting board, which framework embraces a bar having evenly projecting parallel end portions, a bracing plate therefor, and a channel in line directed midway said end portions, and including a 115 revolvable vertical pin on said plate midway its forward edge adapted for lowering and sticking the board for revolving the frame thereon, a plate transverse to the channel having openings in its ends with 120 means for its sliding engagement along the channel and for stopping and releasing it, a pair of lever arms pivoted to the channel and slidably confined in said openings adapt- 125 ed for being swung evenly by movement of the transverse plate, and having a pair of rods pivoted to their swinging ends; the combination of a flexible bar; a pair of arms fastened to its ends and projecting normally therefrom; a pair of curved guide bars fas- 130 tened to the right and left of the frame; cor-

responding curved guide edges on the forward side of said bracing plate and intersecting at said pin, and means on said arms for their sliding engagement with said guides and for the pivotal attachment of said rods thereto: so that the swing of said lever arms springs the flexible bar into curves, the chords of which are limited by the guide bars while the intersecting guides force the bar to bend tangentially, causing the properties of the curves formed to correspond to those of circles or segments thereof and to guide the arms to meet at the pin, and the bar to a half circle formation centering thereat; said bar and guides being provided with scales for degree and lineal measurement for measuring the value of arcs and measuring properties thereof, in connection with which scales and with marking implements said bar, arms and pin are adapted for gauging and ruling circles or arcs thereof in series between a straight line and said half circle formation; means adjustable at different distances from said pin adapted for guiding marking implements in circles or arcs thereof smaller than said half circle formation and, in connection with, and by reference to, said bar, arms, pin and scales, for gauging and ruling such smaller arcs and circles; substantially as described and shown.

2. In a circle gauging instrument, the combination of a frame having a guide plate and right and left guide bars and a channel in line directed midway between them; a pin and bearings therefor in vertical line fastened to the plate midway between the guide edge and having a head and a needle point; a laterally tapering sleeve enclosing the pin between its head and its bearings adapted for being shoved transversely to raise the pin and to permit its being lowered to stick the drafting board for revolving the frame thereon; a normally straight flexible bar, and arms having edges normal to the bar mounted at its ends and provided with lugs affording them sliding engagement with the guide bars and guide plate and with pointers overlapping said guide edges; a screw longitudinally confined lengthwise in the channel and adapted to revolve in bearings at its ends; a transverse plate and means affording it sliding engagement with and along the screw and channel and provided with openings at its right and left ends; a pair of lever arms slidably confined in the openings and pivoted to the channel; a pair of rods connecting said lever arms and arms and provided with offsets for locking the latter to the guide bars; so that by moving the transverse plate the arms may be moved evenly to the pin, and simultaneously the flexible bar to an arc formation of 180 degrees; vertically flexible bars fastened to the arms provided with pen seat members

consisting of sockets having diamond or eye, shaped holes in their floors adapted for the steady seating of marking instruments of differing sizes without attracting ink therefrom and for guiding them about the pin at differing distances therefrom as the frame is revolved, for gauging and ruling circles in series of limited range including circles smaller than said 180 degree arc formation, said flexible bar being provided with a scale adapted for its lineal measurement and for measuring in degrees segments of arcs formed thereby and for gauging properties of arcs formed by the pen seats by reference to said scale and the known degree of curve of said 180 degree arc; a spring-held plate pivotally mounted on said transverse plate provided with release and pull lugs and adapted for releasable engagement with the threads of the screw; and a turning knob member on said screw, there being scale indicia on said guides adjacent the pen seats and on said guide plate, all coacting for the purpose specified.

3. In a circle gauging instrument, the combination of a framework embracing right and left guides and a channel in line directed midway between them; a flexible bar and a pair of arms fastened to its ends provided with means which confine them to sliding engagement with the guides and adapted for throwing the bar into uniform curves when sprung, for gauging and ruling circles in series of limited range; a transverse plate and means affording it sliding engagement along said channel and with openings in its right and left ends; a pair of hook-shaped lever arms pivoted to the channel and slidably confined in said openings; a pair of rods pivoted to the lever arms at one end and provided with offsets at the opposite end which engage overlapping lugs on the arms and lock them to the guides, said lever arms being adapted to be swung by movement of the transverse plate for curving or straightening said bar and having curved shanks affording greater range of fulcrum contact with the plate than the width of the radial zone of said openings, so that the swing of their functional ends is over longer arcs than the arcs of the same radius between whose subtending radii the fulcrum moves; a screw lengthwise in said channel adapted to revolve longitudinally confined therein; a latch pivoted on top of the plate adapted to tip to engagement with the threads of the screw for stopping the plate at intermediate positions on the channel; substantially as described and shown.

4. In a circle gauging instrument, a frame adapted for being moved about on a drafting board and embracing right and left guide bars, a plate having right and left

6

guide edges and a channel provided with pull lugs and situated in line directed midway between said guides; a pin on the plate mounted vertically to revolve adapted for lowering and sticking such board for revolving the frame thereon; a normally straight flexible bar and a pair of arms fastened to its ends having their inner edges projecting normally from the bar and provided with lugs affording them sliding engagement with said guides and with pointers overlapping said guide edges, adapting the arms when the bar is sprung to throw it into uniform curves for gauging and ruling circles in series of limited range; pen seat members mounted on said arms adapted for seating marking implements of differing sizes and guiding them around the pin as the frame is revolved for gauging and ruling circles in series of limited range including a range complementing those possible with the bar; a screw adapted to revolve in said channel in longitudinally confined position; a transverse plate having openings in its ends and being provided with a sleeve member enclosing the screw for affording the plate sliding guided engagement with and along the channel; right and left lever arms pivoted to the channel and slidably confined in said openings and connected by rods with said arms and adapted for being actuated by movement of the plate to change the form of the flexible bar and the distance between the pen seats and the pin; a spring-held latch pivotally mounted on the plate provided with release and pull lugs and a slotted tongue adapted for engagement with the threads of the screw for stopping the plate the flexible bar and guides being provided with scale indicia adapted for measuring the value of the curves of the bar in degrees, their lengths and central angles and the distances of the pen seats from the pin, so that the combined range of application of said bar and pen seats in connection with said scales in gauging and ruling circles extends from a straight line to a circle a half inch or less in diameter; a turning knob member on said screw provided with equally spaced ribs parallel therewith for turning the screw by divisions thereof rib by rib and tallying the revolutions to slowly move said arms by reference to the known number of such revolutions required for a space on the guide scales to given distances that fall between graduation marks on said scales; substantially as described.

5. In a circle gauging instrument, a frame adapted for being moved about on a drafting board embracing right and left guide bars, a plate having intersecting curved guides and a channel fastened to the plate in line directed midway of the guides; a pin pivotally mounted on the frame at the intersection point of said guides adapted for

sticking the board for revolving the frame and provided with means for holding it clear thereof; a normally straight flexible bar having arms fastened to its ends projecting perpendicularly therefrom, and provided with means for their sliding engagement with the guides, and having mounted thereon pen seat members for guiding marking implements about the pin, the arms being adapted for carrying the pen seats towards or away from the pin and to throw the bar into uniform curves as it is sprung, the pen seats and bar being adapted respectively for gauging and ruling circles in smaller and larger mutually complementing series; a transverse plate having openings at its right and left ends and means for its slidable engagement with and along said channel and for stopping and releasing it; a pair of lever arms pivoted to the channel and connected with the arms by rods and slidably confined in said openings and adapted for being actuated by movement of the plate to move the arms; a diaphragm fastened to the frame having corresponding round openings at its top and bottom; a ball encased therein adapted to always protrude through one or both of the openings; a tension plate fastened to the frame to normally bear against the upper opening adapted subject to pressure on the frame to hold the ball in the lower opening with revolving play therein for holding the adjacent portion of the instrument off the drafting board when it is being moved about in use of the bar or revolved in use of the pen seats, and to permit upon such pressure the ball to protrude through the upper opening and allow the frame to come to rest on said board, but otherwise to hold it to serve as a supporting roller for said frame; substantially as described and shown.

6. In a circle gauging instrument, the combination of a framework embracing right and left guides and a channel in line directed midway between the guides; a normally straight flexible bar and a pair of arms fastened to its ends and projecting perpendicularly therefrom and provided with lugs affording them sliding engagement with the guides for carrying the arms towards each other and so guided throwing the bar into uniform curves upon its being sprung, for gauging and ruling circles in series of limited range; a transverse plate and means affording it sliding engagement along said channel and for stopping it thereon and releasing it; a pair of lever arms pivoted to the channel and connected with the arms by a pair of rods, said lever arms being slidably confined in right and left openings in said transverse plate adapting them for being actuated by movement of the plate for moving the arms and curving the bar; a clip adapted to impinge on the flexible bar midway its length; a stay bar having one end

vertically pivoted to the clip; a curved guide fastened to the frame clear of the swing of the arms and centering at said midway point; guide lugs on the stay bar affording 5 it sliding engagement with said curved guide, said stay bar being adapted upon downward pressure thereon for steadyng the flexible bar on the drafting board and for being swung to clear either side of the flexible bar.

10 either in straight or curved form; substantially as described and shown.

7. In a drafting instrument, the combination of a frame, a flexible bar, a center bar provided with a center pin, an adjusting 15 screw mounted on said center bar, an adjusting slide mounted on said center bar and detachably engageable with said screw permitting its adjustment by said screw or independently thereof, actuating levers pivot-

20 ally mounted on said center bar and operatively associated with said slide whereby said levers are actuated by the adjustment of the slide, links connecting the ends of said actuating levers to the ends of said flexible

25 bar, guide arms secured to the ends of said flexible bar and disposed at right angles thereto when said bar is in its normal position, curved guide members on said frame coacting with the ends of said arms, curved 30 guide bars operatively associated with the ends of said flexible bar, a brace for said flexible bar engaging the center thereof, and a segment on which the outer end of said brace bar is adjustably mounted.

35 8. In a drafting instrument, the combination of a frame, a flexible bar, a center bar provided with a center pin, an adjusting screw mounted on said center bar, an adjusting slide mounted on said center bar and detachably engageable with said screw permitting its adjustment by said screw or independently thereof, actuating levers pivotally mounted on said center bar and operatively associated with said slide whereby said

40 levers are actuated by the adjustment of the slide, links connecting the ends of said actuating levers to the ends of said flexible bar, guide arms secured to the ends of said flexible bar and disposed at right angles thereto when said bar is in its normal position, curved guide members on said frame coacting with the ends of said arms, and curved guide bars operatively associated with the ends of said flexible bar.

45 9. In a drafting instrument, the combination of a frame, a flexible bar, a center bar provided with a center pin, an adjusting slide mounted on said center bar, actuating levers pivotally mounted on said center bar and operatively associated with said slide whereby said levers are actuated by the adjustment of the slide, links connecting the ends of said actuating levers to the ends of said flexible bar, guide arms secured to the ends of said flexible bar and disposed at

50 said flexible bar, guide arms secured to the ends of said flexible bar and disposed at

right angles thereto when said bar is in its normal position, curved guide members on said frame coacting with the ends of said arms, curved guide bars operatively associated with the ends of said flexible bar, a 70 brace for said flexible bar engaging the center thereof, and a segment on which the outer end of said brace bar is adjustably mounted.

10. In a drafting instrument, the combination of a frame, a flexible bar, a center bar provided with a center pin, an adjusting slide mounted on said center bar, actuating levers pivotally mounted on said center bar and operatively associated with said 75 slide whereby said levers are actuated by the adjustment of the slide, links connecting the ends of said actuating levers to the ends of said flexible bar, guide arms secured to the ends of said flexible bar and disposed at 80 right angles thereto when said bar is in its normal position, curved guide members on said frame coacting with the ends of said arms, and curved bars operatively associated with the ends of said flexible bar.

11. In a drafting instrument, the combination of a frame, a flexible bar, a center bar provided with a center pin, an adjusting screw mounted on said center bar and detachably engageable with said screw permitting its adjustment by said screw or independently thereof, actuating levers pivotally mounted on said center bar and operatively associated with said slide whereby said levers are actuated by the adjustment 95 of the slide, links connecting the ends of said actuating levers to the ends of said flexible bar, means for maintaining a uniformity of curvature of said flexible bar throughout its adjustment, a brace for said flexible bar engaging the center thereof, and a segment on which the outer end of said brace bar is adjustably mounted.

12. In a drafting instrument, the combination of a frame, a flexible bar, a center bar provided with a center pin, an adjusting screw mounted on said center bar, an adjusting slide mounted on said center bar and detachably engageable with said screw permitting its adjustment by said screw or independently thereof, actuating levers pivotally mounted on said center bar and operatively associated with said slide whereby said levers are actuated by the adjustment of the slide, links connecting the ends of said actuating levers to the ends of said flexible bar, and means for maintaining a uniformity of curvature of said flexible bar throughout its adjustment.

13. In a drafting instrument, the combination of a frame, a flexible bar, a center bar provided with a center pin, an adjusting screw mounted on said center bar and detachably engageable with said screw permitting its adjustment by said screw or in-

dependently thereof, irregularly curved actuating levers pivotally mounted on said center bar and operatively associated with said slide whereby said levers are actuated by the adjustment of the slide, links connecting the ends of said actuating levers to the ends of said flexible bar, and means for maintaining a uniformity of curvature of said flexible bar throughout its adjustment.

14. In a drafting instrument, the combination of a frame, a flexible bar, an adjusting screw disposed transversely of said bar, an adjusting slide detachably engageable with said screw permitting its adjustment

15 by said screw or independently thereof, operating connections from said slide to the ends of said flexible bar, guide arms secured to the ends of said flexible bar, guide members coacting with the ends of said arms, and curved guide bars operatively associated with the ends of said flexible bar, said flexible bar, guide bars, and arm guide members being provided with scale indicia.

16. In a drafting instrument, the combination of a frame, a flexible bar, an adjusting screw disposed transversely of said bar, an adjusting slide detachably engageable with said screw permitting its adjustment by said screw or independently thereof, operating connections from said slide to the ends of said flexible bar, guide arms secured to the ends of said flexible bar, guide members coacting with the ends of said arms, and curved guide bars operatively associated with the ends of said flexible bar.

17. In a drafting instrument, the combination of a frame, a flexible bar, an adjusting slide adjustable transversely of said flexible bar, operating connections from said slide to the ends of said flexible bar, guide arms secured to the ends of said flexible bar, guide members coacting with the ends of said arms, and curved guide bars

operatively associated with the ends of said flexible bar, said flexible bar guide bars, 45 and arm guide members being provided with scale indicia.

18. In a drafting instrument, the combination of a frame, a flexible bar, an adjusting slide adjustable transversely of said flexible bar, operating connections from said slide to the ends of said flexible bar, guide arms secured to the ends of said flexible bar, guide members coacting with the ends of said arms, and curved guide bars 55 operatively associated with the ends of said flexible bar.

19. In a drafting instrument, the combination of a frame, a flexible bar, an adjusting slide mounted for adjustment transversely of said flexible bar, operating connections from said slide to the ends of said bar, and means coacting with the ends of said bar for maintaining uniformity of curvature thereof throughout its adjustment. 60

20. In a circle gauging instrument provided with an operating framework, the combination of a flexible bar adapted for registering upon drawn lines and for guiding markers along its surface, a pair of arms 70 fastened to the ends of the bar adapted for sliding movement on the frame, means on the frame for pulling said ends and arms towards each other to bow the bar, means 75 on the frame for so controlling the movement of the arms that the bar is forced into uniform curve formation throughout, means on the frame and on the bar for measuring by reference respectfully to the 80 position of the arms and the length of the curve formations or sectors thereof of the bar the geometrical values of such formations, substantially as and for the purpose set forth. 75

HERBERT J. ADAMS.
